UNITED STATES PATENT OFFICE

PERCY J. BENBOUGH, OF SAN DIEGO, CALIFORNIA

DESIGN FOR A CASKET HANDLE SUPPORT

Application filed October 11, 1932. Serial No. 45,305. Term of patent 7 years.

To all whom it may concern:

Be it known that I, PERCY J. BENBOUGH, a citizen of the United States of America, residing at San Diego, in the county of San Diego and State of California, have invented a certain new, original, and ornamental Design for a Casket Handle Support, of which the following is a specification, reference being had to the accompanying drawing forming part thereof.

Figure 1 is a front elevational view of my new design for a casket handle support; Fig. 2 is a sectional view on the line 2—2 of Fig. 1, and Fig. 3 is a fragmentary sectional view on the line 3—3 of Fig. 1.

I claim:

The ornamental design for a casket handle support substantially as shown.

In testimony whereof, I have hereunto set my hand at San Diego, California, this 6th day of October, 1932.

PERCY J. BENBOUGH.
